UNITED STATES PATENT OFFICE.

LOUIS PLANER, OF NEW YORK, N. Y.

IMPROVEMENT IN SEWING-MACHINES.

Specification forming part of Letters Patent No. 43,927, dated August 23, 1864.

To all whom it may concern:

Be it known that I, LOUIS PLANER, of the city, county, and State of New York, have invented certain new and useful Improvements in Sewing-Machines; and I do hereby declare that the following is a full, clear, and exact description of the same, reference being had to the accompanying drawings, forming part of this specification, in which—

Figure 1 represents a side elevation of my improved sewing-machine, a part of the table being removed to exhibit more distinctly the working parts beneath the same. Fig. 2 is a front elevation of the same. Fig. 3 is a vertical section, on an enlarged scale, of the crank and connecting-rod as combined for transferring motion to the shuttle and "feed" of the machine.

Similar letters of reference indicate corresponding parts in the several figures.

To enable others skilled in the art to make and use my invention, I will proceed to describe its construction and operation with reference to the drawings.

A represents a horizontal driving-shaft, which is supported in two bearings, *a a*, in the upper part of the machine.

B is a second shaft, arranged in line with the shaft A, and supported in bearings *b b*.

C represents a rock-shaft arranged in the lower part or under side of the sewing-table, and having bearings *c c* attached to the lower part of the machine.

The driving-shaft A and second shaft, B, are both provided with disk-shaped collars D D' at the parts where they approach each other. A stud or pin, *d*, fastened in one of the collars, D, and also fitting in the other collar, D', compels both shafts A and B to move or rotate together.

F represents a crank fastened upon the rock-shaft C; and *f* is a crank-pin secured in the extremity of the crank F, which extremity is slotted and a connecting-rod, E, adjusted therein, so that the crank-pin *f* passes through the connecting-rod E. The other end of this connecting-rod is fitted between the collars D D', upon the pin *d*, and thereby the rocking motion of the shaft C is transmitted from the shaft A. At the other end of this shaft C is fitted a crank, G, which is combined with the shuttle-driver by a connecting-rod, *g*, and thus the shuttle is vibrated by the shaft C.

I represents a cam placed inside the bearings *c c*, upon the shaft C, and this cam acts on the lever *i*, on the rock-shaft M, which moves the feed-lever N, and thus the feed-wheel derives motion from the shaft C by means of the cam I.

The shaft B is also provided with a crank, *o*, and pin *o'* in the front end of the machine, where it approaches the needle-slide. This slide has a peculiarly-shaped slotted piece, O, fixed on it, and in the slot of O is fitted a friction-roller, *o''*, adjusted on the crank-pin *o'*, so that the desired up-and-down motion of the needle and needle-slide is obtained by the crank *o* and pin *o'* upon the shaft B. At the same time the rotating driving-shaft imparts a vibratory motion to the shuttle by means of the connecting-rod E and shaft C. The connecting-rod E is made with conical bearings, as shown in Fig. 3, and the crank-pin *f* is made with a conical portion to fit the bearings in the connecting-rod, one end of the pin *f* being made cylindrical and fitted in one part of the crank, so as to slide in it. The other end of the pin is made with a screw-thread fitting the other part of the crank, and long enough to allow a nut, *f'*, to be applied, and thus whenever the connecting-rod E may have worn loose in its bearings upon the pin *f* this pin may be screwed in a little farther to adjust the bearing of the connecting-rod, and thereby all noise and irregularity in the operation of the said rod is avoided.

In ordinary sewing-machines the motion of the various working parts is produced by means of cams, which necessarily create much friction and cause the machines to work hard. In some machines cranks have been used similar to those above described; but the use of ordinary cranks is objectionable, because they soon wear out and cause a dead-motion, which is detrimental to the correct operation of the machine, and causes much noise if the machines are run at a high speed.

By my invention the advantages of the cam motion and of the crank motion are combined. I retain the cranks in order to reduce the friction, and in order to avoid the dead-motion I have arranged the cranks so that they can be readily adjusted whenever it is desirable. For these reasons I am enabled to work my machine with great velocity without noise and with comparatively little power.

What I claim as my invention, and desire to secure by Letters Patent, is—

The arrangement of the driving-shaft A, the second shaft, B, the crank-pin o', the peculiarly-shaped slotted piece O upon the needle-slide, the collars D D', the connecting-rod E, in combination with the adjustable crank-pin f, crank F, shaft C, connecting-rod g, and crank G, all

constructed and operating in the manner and for the purpose herein shown and described.

LOUIS PLANER.
